ROLL-A-WAY WINDOW SCREEN

Philip W. Zagrodny, Chicago, Ill.

Application January 5, 1948, Serial No. 609

4 Claims. (Cl. 160—27)

1

My invention relates to roll-a-way window screens, demountably attachable to a sash.

An object of my invention is to provide roller type window screens that may be mounted within the window frame at both top and bottom if desired. The said window screens having the means of being detachably secured to the bottom and top edges of the window sash thereof so that when the bottom window sash is raised, or when the top window sash is lowered, the openings between the said window sash and window frame will be closed by window screening.

A further object of my invention is to provide roll-a-way window screens, mounted on spring-urged rollers, so that when the said window sash is closed, the window screen will automatically roll itself away and out of sight on the said spring-urged rollers.

A still further object of my invention is to provide a quick means of locking or unlocking the said window screen into a sealing relationship with the edges of the said window sashes.

A further object of my invention is to provide a screen-retaining moulding which is removably securable to the edge of the window sash and at the same time, in its lowered position, forms a waterproof seal with the window sill. In the said closed position the top of the said screen-retaining moulding is flush with the said window sill.

A still further object of my invention is to provide a resilient seal, designed to fit over the said screen-retaining moulding, for window frames that are too badly worn to permit sealing by the said screen-retaining moulding.

A still further object of my invention is to provide a closure means, attachable to the upper edge of the lower window sash, to prevent insects from entering through the space between the said window sash and window pane while the said windows are open.

A further object of my invention is to provide roll-a-way window screens, demountably attachable to a sash, that may be economically produced in large numbers to fit any type or size of sliding windows.

Other objects and advantages embraced in my invention will be disclosed in the following description and the accompanying illustrations, in which like parts are designated by like numerals, and in which

Fig. 1 is the front view of a sliding type window, with parts cut away, and showing my roll-a-way window screens attached to the sash thereof.

Fig. 2 is a side view, partly in cross section,

2

looking in the direction of the arrows on line 2—2 on Fig. 1.

Fig. 3 is an enlarged fractional perspective view of portions of the principal elements of my invention, with parts cut away, to show their operation.

Fig. 4 shows a fractional perspective view of a modification of one of the elements of my invention.

Fig. 5 is a vertical cross-sectional view taken substantially on line 5—5 on Fig. 1, and showing the closure means used in connection with my invention.

Fig. 6 is an enlarged vertical cross-sectional view taken substantially on line 6—6 on Fig. 1, and showing the locking means for releasably securing the screen to the window sash.

Fig. 7 is a top view of a portion of my invention, partly in cross section, looking in the direction of the arrows on line 7—7 on Fig. 2.

Fig. 8 is a top cross-sectional view of a portion of my invention taken substantially on line 8—8 on Fig. 1, and showing the screen guide means used in connection with my invention.

Referring to the illustrations, my invention is generally designated 9, and consists of a length of window screen 10 of either metal or plastic wire. The lower edge of the said window screen 10 is looped at 11 and sewed at 12 to permit a roller attaching rod 13 to be inserted therein.

A number of cutouts 14 in the looped edge 11 provide clearance for the looped ends 15 of a number of flat coil springs 16 to be secured to the roller attaching rod 13; the said spring ends 15 protrude from slots 17 in a hollow roller 18.

The said hollow roller 18 is rotatably mounted upon a roller shaft 19; the outer ends of which are formed into flats 20 to provide holding and locking means within the slot 21 on the ends 55 of the roller casing 22. The said ends 55 are partly cut away to permit the removal of the screen roller 18 when desirable, as shown in Fig. 3.

The said roller casing 22, together with the roller 18, are mounted upon the underside of window sill 23, or upon the top side of the top of window frame 56, as shown in Figs. 1 and 2. The said flat coil springs 16 are mounted prewound at intervals upon the roller shaft 19, within the roller 18 and, by means of the ends 15 extending through the slots 17, provide tension to the said roller 18, causing a rotational pull in a counter-clockwise direction, as shown in Fig. 3.

Since the spring ends 18 are attached by means of roller attaching rod 13 to the screen 10; therefore when the said screen 10 is released from

window sash 36, or when the said window sash is lowered, the said screen 10 will wind itself upon the roller 18 within the casing 22.

A longitudinal opening 24 is provided in window sill 23 to allow the screen 10 to pass therethrough. The edges 25 of opening 24 are beveled to provide seating for a screen-holding moulding 26; the said screen-holding moulding 26 is provided with tapered sides 53 to make a sealing contact with said beveled seating 25. A central groove 27 runs throughout the length of moulding 26, in the center of which is formed a depending flange 28.

Attached along the bottom edge of flange 28 is an inverted U-shaped screen-retaining keyway 29, in which a removable key rod 31 retains the looped top edge 30 of screen 10. Thus, by means of said removable key rod 31, the top edge of screen 10 may be quickly secured to, or removed from, the screen-holding moulding 26. Formed on the top surface, one at either end of moulding 26 are sash attaching wedges 32, which are insertable into triangularly-shaped wedge slots 33 in the two bottom corners of the said window sash 36. The said sash attaching wedges 32 may be locked within the triangular wedge slots 33 by a wedge-locking means 34.

The said wedge-locking means 34 consists of a cylinder 37 mounted within an opening 35 in sash 36 at a point in alignment with the sloping edge of wedge 32. A keyway 39 is formed in the side of wedge 32 to communicate with a slot 38 in cylinder 37. A wedge-holding bolt 40, which is slidably contained in cylinder 37, provides the locking means with the said keyway 39, and is held in the said locking position by a coil spring 42 in the end of cylinder 37, as shown in Figs. 3 and 6.

By depressing and rotating the lock manipulating extension 44 upon the end of said wedge-holding bolt 40, a wedge release slot 41 upon the said bolt 40 is brought into registry with keyway 39, releasing the window sash 36 from screen-holding moulding 26; the said wedge-holding bolt 40 is locked in its depressed inoperative position by means of a bayonet lock 43 in the outer end thereof.

Figs. 5 and 7 show details of a closure means 46 provided to close the opening between window pane 49 and window sash 36 when one or both of the window sashes are open. The said closure means 46 consists of a strip of screening, having a rubber wiper tip 47, and attached by means of metal stays 48 to the top edge of window sash 36. A screen guide and sealing means is illustrated in Figs. 1 and 8. The inner side portions of window frame 50 are rabbeted at 50, as shown in Fig. 1.

U shaped metal screen guides 51 are mounted within the rabbeted portions of the frame 50 to act as guiding and sealing means for the protruding selvaged side edges 52 of screen 10 as it is raised or lowered with the window sash 36.

If the window frames are of wood and if the sills thereof are badly worn, a rubber sealing cap 45 is provided to fit over the screen-holding moulding 26, as illustrated in Fig. 4. The said rubber sealing cap means 45 is provided with overlapping edges 54 to prevent moisture or dirt from penetrating into opening 24.

To use my roll-a-way window screen, the window-screen together with the roller 18 and the casing 22 are mounted as shown in Fig. 3 onto the underside of window sill 23 when mounted for attachment to the lower window sash 36. The

lower edge of screen 10 is attached by means of roller attaching rod 13 and spring ends 15 to the said roller 18. The upper edge of the said screen 10 is attached by means of key rod 31 within screen-retaining keyway 29 on screen-holding moulding 26. When released, the said screen 10 will be automatically rolled upon roller 18, pulling the sealing moulding 26 into sealing contact with the beveled seating 25 in window sill 23.

The wedge-holding bolt 40 is locked in its depressed, inoperative position, allowing the window sash 36 to be lowered into a locking position with the said sash attaching wedges 32. Rotation of lock manipulating extensions 44 releases wedge-holding bolts 40 locking the sash attaching wedges 32 to the window sashes 36. When the window sash 36 is raised, screen 10 will be simultaneously raised therewith and, when the said sash 36 is lowered, the said screen 10 will automatically wind itself upon spring-urged roller 18. In like manner, the upper window sash may be similarly equipped with roller screen structure and will operate in a manner similar to that of the said lower window screen.

The above described roll-a-way window screen, together with the window sashes and frame, provide a completely insect-proof screening to the windows when open, with the added advantage of clear view windows with the screen rolled away and out of sight during wet weather when the windows are closed. The screens are not exposed to the weather and therefore will last longer.

My roll-a-way window screen, demountably attached to a sash, may be attached to any type, wood or metal, window sash and frame, or may be manufactured therewith as a unit.

I believe that I have herein shown and revealed the nature of the construction and operation of my invention in rather succinct terms and, inasmuch as the same is susceptible of many modifications, alterations, and improvements, I hereby reserve the right to all such modifications, alterations, and improvements which come within the scope and spirit of my invention, as well as those falling within the province and suggestions of the accompanying drawings, as well as those lying within the purview of the foregoing description; my invention to be limited only by the appended claims.

Having thus described and revealed my invention, what I claim as new, and desire to secure by Letters Patent, is:

1. In a roll-away screen demountably attachable to a window sash operating in a window frame, sill means mounted in the opening of the said window frame and provided with bevelled seat means terminating in a narrow longitudinal opening, screen retaining moulding means removably securable to the bottom edge of the said window sash and provided with tapered side portions, and resilient sealing cap means encasing the said screen retaining moulding means effectuating sealed relationship between the said sill means and the said window sash when closed.

2. In a roll-away screen demountably attachable to a window sash operating in a window frame, sill means mounted in the opening of the said window frame and provided with bevelled seat means terminating in a narrow longitudinal opening, screen retaining moulding means removably securable to the bottom edge of the said window sash and provided with tapered side portions, resilient sealing cap means encasing the said screen retaining moulding means effec-

tuating sealed relationship between the said sill means and the said window sash when closed, wedge-locking means secured to the said screen retaining moulding means, slotted portions in the bottom edge of the said window sash, and bayonet lock means fitted to the said window sash and engaging releasably the said wedge-locking means.

3. In a roll-away screen demountably attachable to a window sash operating in a window frame, sill means mounted in the opening of the said window frame and provided with bevelled seat means terminating in a narrow longitudinal opening, screen retaining moulding means removably securable to the bottom edge of the said window sash and provided with tapered side portions, and resilient sealing cap means encasing the said screen retaining moulding means effectuating sealed relationship between the said sill means and the said window sash when closed, the said bottom edge being of concave cross-sectional configuration, the said resilient sealing cap means being of convex cross-sectional configuration to fit sealably the said bottom edge.

4. In a roll-away screen demountably attachable to a window sash operating in a window frame, sill means mounted in the opening of the said window frame and provided with bevelled seat means terminating in a narrow longi-

tudinal opening, screen retaining moulding means removably securable to the bottom edge of the said window sash and provided with tapered side portions, resilient sealing cap means encasing the said screen retaining moulding means effectuating sealed relationship between the said sill means and the said window sash when closed, wedge-locking means secured to the said screen retaining moulding means, slotted portions in the bottom edge of the said window sash, and bayonet lock means fitted to the said window sash and engaging releasably the said wedge-locking means, the said bottom edge being of concave cross-sectional configuration, the said resilient sealing cap means being of convex cross-sectional configuration to fit sealably the said bottom edge.

PHILIP W. ZAGRODNY.
